UNITED STATES PATENT OFFICE

125,014

DESIGN FOR A MAGNETIC ADVERTISING NOVELTY OR SIMILAR ARTICLE

Albert J. Bates, La Crosse, Wis.

Application May 3, 1940, Serial No. 92,108

Term of patent 3½ years

To all whom it may concern:

Be it known that I, Albert J. Bates, a citizen of the United States and a resident of the city of La Crosse, in the county of La Crosse and State of Wisconsin, have invented a new, original and ornamental Design for a Magnetic Advertising Novelty or Similar Article, of which the following is a specification, reference being had to the accompanying drawing, forming a part thereof.

On the drawing:

The design herein is a magnetic advertising novelty comprising a unit of magnetically coupled parts, as shown.

I claim:

The ornamental design for a magnetic advertising novelty or similar article, as shown and described.

ALBERT J. BATES.
